GUIDING OR SPACING OF YARNS IN
WARP FORM

Joanny Jabouley, London, England, assignor, by
mesne assignments, to Celanese Corporation of
America, a corporation of Delaware

Application February 8, 1933, Serial No. 655,697
In Great Britain February 20, 1932

3 Claims. (Cl. 139—13)

This invention relates to textile appliances, and in particular to appliances for spacing threads arranged in warp form.

The object of the invention is to provide a thread spacing device which is simple in character and permits ready threading-up while offering a smooth and unobstructed passage for the thread.

The device according to the invention comprises a coiled spring whose coils are spaced apart at a distance appropriate to the density of the threads in the warp, so that the threads can be passed through the space between the coils or through the coils themselves and be guided thereby. The device may be used either with a single thread for each coil or coil space, or if desired two or more threads may be led together through each coil or space.

The coiled spring may be mounted in any convenient manner, for example by being bound with cord or wire to one or more rods adapted to be mounted in the machine or device in which the spring is to be used. If desired, means may be provided for holding the spring in a more or less extended condition so as to provide for a variation in the warp density or in the warp width. Thus, the ends of the spring may be secured to the support by screws adjustable in position along the support so as to maintain the spring at any desired length and with any desired coil spacing.

The warp spacing device according to the invention may be used as a spacing reed in a large number of textile machines. For example it may be employed in beaming, sizing or other machines in which threads are treated as a warp. The device is, however, of particular service in circular machines in which a warp of threads is used in cylindrical form, as for example in circular looms. Thus, the coiled spring spacing device may be used to guide warps proceeding from a set of beams or sectional beams in a circular loom, the device enabling the threads to be guided as an even sheet or sheets under uniform tension to the point at which weft is inserted. In such a machine a single spring may extend round the whole periphery of the loom, but more conveniently, the spring is formed in sections each extending over say a quarter of the loom periphery.

The spring is preferably mounted in such a manner as to be readily removable so that warps of different density can readily be accommodated by interchange of springs.

The spacing device according to the invention may be used both in looms in which the warps

remain stationary while the shuttles revolve about the axis of the loom, and in looms in which the warps themselves rotate. Thus, for example it may be used in looms of the type described in U. S. applications S. Nos. 629,913, 629,914 and 629,915 all filed 22nd August, 1932, and, especially when employed in conjunction with the warp spacing finger described in U. S. application S. No. 629,916 filed 22nd August, 1932, is of great service in enabling very even fabrics to be woven on circular looms.

The invention will now be described in greater detail with reference to the accompanying drawing, which shows the spacing device according to the invention mainly with reference to its use in a circular loom of the type described in U. S. application S. No. 629,914. Sufficient of the loom described therein is shown to illustrate the application of the invention.

According to the drawing:

Figure 1 is a part cross-sectional elevation of the device according to the invention;

Figure 2 is a cross-sectional elevation in larger scale of a detail of Fig. 1;

Figures 3 and 4 are elevation and plan views respectively showing the position of the warp threads relative to the spacing device;

Figure 5 shows in plan an alternative detail of the invention; and

Figures 6 and 7 show in elevation and part sectional plan respectively further alternative details of the invention.

As shown in Figure 1, warp threads 10 upwinding from a warp beam (not shown) are divided into two sheets 11, 12, by a circular lease-rod 13 from which they proceed downwardly in divided form through a reed 14 to the fabric 15. Shedding is performed in the manner described in U. S. application S. No. 629,914, the reed 14 being so constructed as to provide free passage for certain of the warps along the reed spaces, while allowing only a limited movement to the remainder of the warps. Rotatable discs 20, 21, arranged at different points round the loom inside and outside the warp circle press against the warps, sheet 11 of which is free to move in the reed spaces and is pressed alternately inwardly and outwardly to separate it from sheet 12. A shedding motion is thus commenced, and is completed by the foremost end of a tapering boat-shaped shuttle 22 which enters between the warps and forces them apart.

On leaving the lease-rod 13 the threads of the two sheets 11 and 12 are engaged and guided by the coils of a coil-spring 23 which extends round

the loom. The tension in the spring 23 is such that the coils are spaced apart at a distance appropriate to the density of the threads in the warp, so that the threads 11 and 12 (shown in elevation in Figure 3, and in plan in Figure 4) pass between the coils and cannot become dislodged therefrom. In Figure 4, two threads 11, 12 per coil are spaced by the spring, but any number of threads, according to the density of the warp 10 and/or the density of the spring coils, may enter each coil.

The spring 23 is bound at 30 or otherwise joined to a circular round rod 24 extending round the loom. The combination thus formed is maintained in position by two further circular round rods 25, 26, the upper, 25, of which is welded to the outer edge of an annular plate 27, extending round the loom, while the lower 26, is joined to and carried by arms 28 (Figure 2) disposed at 20 various points around the loom. The rods 25, 26 are nipped into the neck formed between the spring 23 and the rod 24, by bolts 29 which clamp the annular plate 27 and the arms 28 to a supporting plate 32, which is suspended from an adjustable pillar 33 slidable in a sleeve 34 into which it is locked in position by a bolt 35. As many pillars 33 and sleeves 34 as are required to support the weight of the spacing means are suspended at points round the loom from a plate 36 30 outstanding from the central shaft 37 of the loom. The coil-spring 23 is thus adjustable in height relative to the reed 14 and may be adjusted to suit different types of warps being woven.

The lease-rod 13 is supported at points around 35 its circumference by hook-like members 38 (one only shown) pivoted at 39 in a slot 40 formed in a member 41 upstanding from the plate 27. The slot 40 in the member 41 enables the hook to be adjusted in height in order to regulate the height 40 of the lease-rod 13 relative to the reed 14.

The coil-spring 23 may be formed in sections 45 around the loom, (conveniently in quarter sections), or may be continuous throughout its length. In the latter case the ends are soldered or otherwise joined together in the manner shown in Figure 4, a block of solder, or similar material, being run a short distance into the ends of the spring.

Alternatively, the extremities of the spring may 50 be formed into ring-like projections 42 (Figure 5), which are secured in overlapping relation by a bolt 43 housed within a slot 44 in a circular member 45 extending round the loom. This method of securing the ends of the spring is 55 particularly suitable when the spring is mounted in sections (e. g. four) round the loom, as the section can simply and easily be replaced by a new section or one with different coil spacing. In order to provide support for the spring sections, the member 45 to which the ends of the spring 60 are secured is formed with an outstanding rim 46 along its lower edge, against which the spring bears.

The spring is thus supported by the rim 46

which protrudes enough to support the spring, but does not interfere with the passage of the thread through the spring. The slot 44 allows of adjustment of the coil spacing of the spring so that warps of different density can be accommodated simply by varying the tension in the spring. 5

Any desired variation in the length of the springs may be effected provided that the distance between the extremities is not so great as to interfere with the even spacing of the warp 10 threads. Short distances, however, do not affect the even spacing of the threads within the fabric as any uneven effect is corrected readily when the threads are passing through the reed 14.

Figures 6 and 7 illustrate methods of supporting 15 and adjusting a straight coiled spring adapted to space and guide a flat sheet of warps.

The extremities 47 of the spring are formed into ring-like projections as explained with reference to Figure 5, and are secured by a bolt 48 to a 20 supporting member 49 either slotted, as indicated at 50 on the left hand side of Figure 6, or perforated, as indicated at 51 on the right hand side of Figure 6. Thus, by changing the position of the bolt 48 along the slot 50, or to another hole 25 51, the spring can be tightened or slackened as required in order to accommodate a change in the density or in the width of the warp being woven.

In order to support the spring along its length the member 49 is provided with an outstanding 30 rim 52.

What I claim and desire to secure by Letters Patent is:—

1. In a circular loom, warp spacing means comprising a coil spring extending round the loom, 35 so arranged that the coils are spaced apart at a distance appropriate to the density of the threads in the warp, a supporting rod extending round the loom concentric with said spring, means connecting the spring to said supporting rod, and supporting means adapted to nip into the space between said rod and said spring to hold said spring in position in the loom.

2. A warp spacing device for circular looms, comprising a supporting rod in the form of a ring 45 extending round the loom, a coil spring extending round the loom and lying exteriorly of the supporting rod and in contact with said rod, the coils of the spring being spaced apart at a distance appropriate to the density of the threads 50 in the warp, and tie means binding the coils of the spring to the rod.

3. A warp spacing device for circular looms, comprising a supporting rod in the form of a ring 55 extending round the loom, a coil spring extending round the loom and lying exteriorly of the supporting rod and in contact with said rod, the coils of the spring being spaced apart at a distance appropriate to the density of the threads in the warp, tie means binding the coils of the spring to the rod, and an adjustable mounting for the spacing rod to provide for adjustment of the position of the spring within the loom.

JOANNY JABOULEY.
